Primary Examiner — Cynthia M. Chin

(57) **CLAIM**

The ornamental design for a multi-functional educational ornamental toy bead, as show and described.

DESCRIPTION

The patent or application file contains at least one drawing executed in color. Copies of this patent or patent application publication with color drawing(s) will be provided by the Office upon request and payment of the necessary fee.

FIG. 1 shows a side view of the bead showing my new design;

FIG. 2 shows a perspective side view where the bead is slightly tilted to the right side;

FIG. 3 shows the bottom half of the bead, shown separately for ease and clarity of illustration;

FIG. 4 shows the top half of the bead, shown separately for ease and clarity of illustration; and,

FIG. 5 is a cross-sectional view taken from line 5-5 of FIG. 1.

The screw threads and inside of the bead does not form part of the claimed design.
